C. H. WILLIAMSON,
 MEANS FOR SECURING GRAB IRONS AND LADDER TREADS TO RAILWAY CARS.
 APPLICATION FILED JULY 30, 1915.

1,178,368.

Patented Apr. 4, 1916.

UNITED STATES PATENT OFFICE.

CLARENCE H. WILLIAMSON, OF ALTOONA, PENNSYLVANIA.

MEANS FOR SECURING GRAB-IRONS AND LADDER-TREADS TO RAILWAY-CARS.

1,178,368.

Specification of Letters Patent.

Patented Apr. 4, 1916.

Application filed July 30, 1915. Serial No. 42,737.

To all whom it may concern:

Be it known that I, CLARENCE H. WILLIAMSON, a citizen of the United States, residing at Altoona, in the county of Blair and State of Pennsylvania, have invented certain new and useful Improvements in Means for Securing Grab-Irons and Ladder-Treads to Railway-Cars, of which the following is a specification.

10 This invention relates to railway cars and has for its primary object improved means for attaching hand holds, grab irons and ladders to the sides of cars without destroying the inside finish of the same.

15 Another object of this invention is to provide improved and adequate means of replacing hand holds, grab irons and ladders with a minimum of expense and labor, thus providing a device that is economical and at 20 the same time efficient and durable.

25 A still further object of the invention is to provide a base portion which is adapted to be securely attached to the side of the car, as well as having ample means for attaching the grab iron or handhold to the same.

With these and many other objects in view, which will be readily apparent to persons skilled in the art, the invention consists in the novel construction, combination and arrangement of parts hereinafter more fully described, illustrated and claimed.

The essential features of the invention involved in carrying out the objects above 35 stated are susceptible to some structural change or modification without departing from the spirit or scope of the invention as defined by the appended claim, but a preferred and practical embodiment thereof is 40 shown in the accompanying drawings, in which—

Figure 1 shows a plan view of this improved grab iron or hand hold attaching means together with a grab iron or hand hold attached thereto. Fig. 2 is a sectional view taken on the line 2—2 of Fig. 1. Fig. 3 is a sectional view taken on the line 3—3 of Fig. 1. Fig. 4 shows a portion of a car end having this improved grab iron or hand hold attaching means applied thereto. Fig. 5 is a horizontal sectional view through one of the base members of the present device.

Like reference numerals refer to similar parts throughout the several figures of the drawings.

In carrying out this invention no change is contemplated in the usual car side construction, or car end construction, nor is it the intention to destroy the inside finish of the car to which it is attached in renewing 60 handholds or grab irons, and to this end there is provided an arched base portion designated by the numeral 10, adapted to be securely fastened to the car side, or to the car end, 11, through the medium of rivets 12. The base 10 is further provided with an up-standing oblong central portion 13, having a recess portion 14 adapted to receive the bolt head 15, which is positioned and locked against rotation in the guideway 65 formed between the abutment lugs 16 arranged beneath the top edge of the slot 19 and extending parallel to the sides thereof, and terminating at the open end of the slot in the depending shoulders 16^a, for the purpose of preventing rotation of the bolt 17, when the nut 18 is removed. The slot 19 through which the bolt 17 enters is of such a depth that when the hand hold or grab iron base 20, is positioned on the base 10, the 70 inside edge of the hole 21 in the grab iron or hand hold will fall in line with the bottom of the slot 19 in the base 10. It will be obvious from this construction that longitudinal as well as transverse movements of 75 the grab iron or hand hold are prevented.

The base 10 is preferably provided with an inward projecting nose 22, adapted to act as a support for the heel 23 of the grab iron or hand hold 24.

In removing this grab iron or hand hold from the side, or end of the car, all that is required is to remove the nuts 18 thus permitting the grab iron or hand hold to be lifted off the base.

From the foregoing description it is thought that the many advantages of the herein described invention will be readily apparent and what I claim and desire to be secured by Letters Patent is.

A grab iron for car bodies comprising a handhold bar having oppositely arranged perforated attaching ears, a pair of anchoring base members, each of said members

comprising an arched body portion having a slot, oppositely disposed attaching ears, and a depending shoulder at the edge of said body on opposite sides of the slot, and fastening bolts having their heads located within the arched body portion behind said depending shoulder, while the shanks thereof project through said slot and the perforated attaching ears to receive a nut for fastening the grab iron to the anchoring base 10 members.

In testimony whereof I affix my signature in presence of two witnesses.

CLARENCE H. WILLIAMSON.

Witnesses:

B. C. McCORMICK,
JAMES T. HANLON.
